INVENTOR.
ALFREDO E. BOSSERDET
BY
Parker & Burton
ATTORNEY.

UNITED STATES PATENT OFFICE.

ALFRED E. BOSSERDET, OF DETROIT, MICHIGAN, ASSIGNOR OF ONE-HALF TO EDWARD HUNTER, OF DETROIT, MICHIGAN.

PLUMB BOB.

Application filed April 7, 1926. Serial No. 100,242.

My invention relates to improvements in plumb bobs.

An object is to provide a plumb bob of improved design wherein a reel upon which the plumb line is wound is mounted within the interior of the bob and has a bearing at each end of the side wall of the bob and extends beyond such bearings and is provided at each end with a thumb piece, and which reel is held axially by a spring to be locked against rotation through interlocking lugs and recesses provided on one of the thumb pieces of the reel and the adjacent side wall of the bob.

15 A removable end closure is provided for the hollowed out end of the bob and the plumb line runs freely therethrough. The plumb line of my improved bob is completely contained within the interior thereof, and, therefore, is prevented from becoming entangled with other tools carried in the tool chest of the workman.

The construction is exceedingly simple. The reel is readily accessible and may be 25 easily wound and unwound and automatically locks the unwinding of the plumb line.

Other meritorious features of my improved plumb bob will appear from the following specification, appended claims and 30 accompanying drawing, in which:

Figure 1 is a side elevation of my improved plumb bob.

Fig. 2 is a side elevation of the same article taken at right angles to the view in 35 Fig. 1.

Fig. 3 is a vertical sectional view through my improved plumb bob.

Fig. 4 is a perspective of the plumb bob with the cap removed.

40 Fig. 5 is an enlarged perspective of one of the thumb pieces of the reel.

It is my purpose to provide a plumb bob of simple, durable construction, wherein the plumb line is contained within the interior 45 of the bob and may be withdrawn as desired. The construction is such that tension is maintained on the reel to lock the same against rotation but the reel is easily operable to permit winding or unwinding 50 of the plumb line.

In the embodiment of my invention illustrated in the drawing, the body of the plumb bob is indicated as 10. In exterior appearance it is of conventional design and it is

hollowed out from the top as at 12, providing a well which has a removable closure cap 14 threaded into a threaded opening 16 at the top of the well. This closure cap has an axial passageway 18 through which the plumb line freely passes. 55

There is a reel 20 which is mounted within the bob extending transversely of the well 12 and which has a bearing at each end within the side walls of the bob as at 22. The plumb line 24 is secured to the reel and extends through the opening 18 in the closure cap. The reel extends at each end beyond its bearing in the side wall of the bob and is provided at each end with a thumb piece. One of these thumb pieces, 70 such as 26, may be permanently secured to the reel if desired, and an expansion spring 28 is interposed between such thumb piece and the reel to exert pressure on the reel through the thumb piece 26. On the 75

opposite end of the reel is provided a removable thumb piece 30 which is threaded onto a reduced threaded end extension 32 of the reel. This thumb piece 30 is provided with a pair of opposed lugs 34 which are 80 adapted to be received within opposed recesses 36 formed in the side wall of the bob adjacent to the bearing opening 22. When the lugs 34 of the thumb piece are disposed within the recesses 36 the reel is 85 locked against rotation.

In Fig. 3 the plumb line is shown as being completely unwound. Normally the plumb line is all wound upon the reel within the bob and the loop only projects exteriorly 90 of the bob, as appears in Figs. 1 and 2. The spring 28 normally holds the reel endwise to retain the lugs 34 within the recesses 36, locking the reel against rotation. When it is desired to unwind the required portion 95 of the plumb line the reel may be held axially against the tension of the spring 28 and rotated to wind or unwind the plumb line as desired.

The reel is readily accessible for removal. 100 The closure cap 14 may be removed, the plumb line unwound, the removable thumb piece removed from the reel, and the reel removed from the bob.

What I claim is:

1. A plumb bob hollowed out to provide a well, a reel mounted within such well extending transversely thereof and having a 105

bearing at each end in the side wall of the bob, said reel extending at each end beyond said bearings and having a thumb piece at each end, an expansion spring around the reel between one thumb piece and the adjacent side wall of the bob, there being opposed recesses in the opposite side wall of the bob adjacent the reel bearing, and opposed lugs upon the adjacent thumb piece adapted to be engaged in said recesses to hold the reel against rotation.

2. A plumb bob hollowed out at one end, a removable closure for such end of the bob provided with an axial passageway, a reel mounted within the hollowed out end of the bob, a plumb line wound upon the reel and extending through said axial passageway in the closure, said reel having a bearing at each end in the side wall of the bob and extending beyond such bearing and provided at each end with a thumb piece, one of said thumb pieces being in the form of a thumb nut threaded onto a threaded end of the reel and provided with a pair of wing-like projections, said bob provided with a corresponding pair of recesses adjacent to the bearing for the reel adapted to receive the

projections on the thumb nut to lock the reel against rotation, a spring on the opposite end of the reel interposed between the thumb piece and the side wall of the bob to hold the reel axially to engage said projections within said recesses.

3. A plumb bob hollowed out interiorly from one end and having a reel positioned transversely of said hollowed out portion and extending at each end beyond the side wall of the bob, a removable end closure for such hollowed out end of the bob, a plumb line wound upon the reel and extending through said end closure, thumb pieces on opposite ends of the reel, said reel and bob provided, one with lugs and the other with cooperating recesses adapted when engaged by the lugs to prevent rotation of the reel, a spring holding said reel axially to engage said lugs and recesses to prevent rotation of the reel, said reel adapted to be moved axially counter the tension of said spring to place the same in position for rotation.

In testimony whereof, I sign this specification.

ALFRED E. BOSSERDET.
